[57] CLAIM

The ornamental design for an electric connector, as shown and described.

DESCRIPTION

FIG. 1 is a top plan view of the electric connector showing our new design;

FIG. 2 is a bottom plan view thereof;

FIG. 3 is a front view thereof;

FIG. 4 is a right side view thereof;

FIG. 5 is a rear view thereof, and;

FIG. 6 shows a perspective view thereof.

The left side view appears symmetrical with the right side view,
